UNITED STATES PATENT OFFICE.

CHARLES SELDEN, OF TOLEDO, OHIO.

MULTIPLEX TELEGRAPHY.

SPECIFICATION forming part of Letters Patent No. 270,990, dated January 23, 1883.

Application filed September 9, 1882. (No model.)

To all whom it may concern:

Be it known that I, CHARLES SELDEN, a citizen of the United States, and a resident of Toledo, in the county of Lucas and State of Ohio, have invented certain new and useful 5 Improvements in Multiplex Telegraphs, of which the following is a specification.

My invention consists of certain novel combinations of apparatus, as hereinafter described and claimed, whereby two messages 10 may be sent in each direction over the same wire without interfering with one another.

The drawing is a diagram illustrating the manner in which the various parts are combined and connected.

T' T² indicate the two levers of the transmitting apparatus, each operated in the ordinary way by a local electro-magnet key and battery, K' being the key for transmitter T' 20 and K² the key for transmitter T². These transmitters are suitably constructed and connected to one another and to the two sections M B' M B² of a main battery for the purpose of sending the following combination of currents: When both keys are at rest no current is to line. When K' is depressed a current of positive polarity is sent to line. When K² is depressed a current of the opposite polarity and approximately the same 25 strength is sent to line. When both keys are depressed together a current of positive polarity and of a strength greater than that sent by either key is transmitted. In the present instance the current-strength is that of both main batteries.

Transmitter T' is provided with two sets of continuity-preserving transmitting-points, (indicated at a b,) each set consisting of the ordinary hook, spring normally resting against the hook, and stop arranged in the path of the spring, so that when the lever is operated the spring comes into contact with said stop and is simultaneously removed from contact with the hook. For the sake of simplicity the stop will be termed the "front" and the hook the "back" contact. The transmitting-points b are suitably insulated from the set a in any well-known or desirable manner.

Transmitter-lever T² is provided with three 50 sets of transmitting-points, c d e, the hooks and springs of all three sets being mounted thereon in any desired manner, and also suitably insulated.

The manner in which the various parts are connected will be best explained by detailing 55 the path of the current in the various positions of the transmitters. Normally the parts are in the position shown and the contact between the spring and the hook of every set of points a b c d e is closed. The circuit from the 60 main line to earth is then through back contacts of a and c directly to earth. Both main batteries are disconnected, the front contacts at a and c being open. If transmitter T' be operated by closing key K', main battery M 65 B' is put to line with a positive polarity, its circuit being through front contact at a to line, and through back contact at d, transmitter T², to earth. The front contact at b is also closed; but no effect is produced thereby under 70 these conditions.

When transmitter T² is operated main battery M B² is put to line with a negative polarity through front contact at c and back contact at a of transmitter T', which is under this 75 condition supposed to be at rest. The opposite pole of the battery is connected to earth through back contact at b, transmitter T'. The back contacts at d e are at the same time broken; but no effect is produced under this 80 condition. When both keys are operated together main batteries M B' and M B² both flow to line with a positive polarity through front contact at a, their other pole being connected to earth through the front contact at e, transmitter T², and the front contact at b, transmitter T'. The back contacts at d and b are at this operation both broken, the purpose being to break both connections of wire 8 to earth, one of which connections—viz., back contact 90 of b—is employed when battery M B² alone is put to line by transmitter T², and the other of which—viz., back contact of d—is used when battery M B' alone is put to line by the operation of transmitter T'. 95

Other constructions and arrangements of transmitters and batteries might be used for producing the above-described play of currents for use with the arrangement of receivers to be now described. As intimated, it is not necessary that the batteries M B' M B² should be of the same strength, although they are here so shown.

At the receiving end of the line, A A' indicates a polarized relay of any desired construction, the armature-lever of which is provided 105

with a retracting-spring, G. This relay is adapted to respond to currents of positive polarity, and by overcoming the action of the retractor G to close the points T³ T⁴, thus completing the circuit of the local battery V, which operates the sounder U. Spring G is adjusted so that a current either from battery M B' alone or from both batteries will close the contacts T³ T⁴. A negative current will draw the armature in the other direction, and will assist spring G in keeping the local circuit broken.

B B' indicates a second polarized relay, the armature-lever of which plays between two contact springs or levers, L L', which are adapted, as indicated, to close a shunt or short circuit for the local battery P when they are both in contact with connected stops K K'. The relay-armature of B B' is drawn into contact with lever L by the action of a negative current from battery M B², and separates said lever from contact-stop K, thus breaking the short circuit of the local battery P and causing the sounder to operate. Its movement in so doing is opposed by spring D², applied to the armature-lever, and by spring F², applied to the spring or lever L, which springs are, however, so adjusted as to act only to restore the parts to their normal position with certainty, and are not sufficient to hold the relay-armature against the action of its magnet when a negative current from battery M B² alone is flowing to line.

When a positive current from battery M B' flows to line the lever of B B' is thrown in the opposite direction and tends to separate the lever L' from its contact-stop, but is prevented from so doing by the action of the spring E³ applied to L', which is adjusted to such a strength that it can not only effectually resist the action of spring D², but also of said spring D² when assisted by the action of a positive current from battery M B'. A positive current from both batteries M B' M B² is, however, sufficient to overcome the tension of the spring E³, and thus cause a separation of L' and K', so as to compel the current of the local battery P to flow in sounder M. The tension of spring E³ may, however, be made so great that, unassisted, the relay, even when acted upon by the current from both batteries, would be able to overcome it. To allow this to be done, and to also provide a means of assisting the action of the relay-armature of B B' when affected by the double positive current, (even when retracting-spring E³ is adjusted below the tension of both batteries,) so as to secure promptitude and certainty of action, I propose to employ a supplemental relay, C, which is by preference a neutral relay, but might be a polarized one, and which controls a local magnet, O, so as to allow the latter to act at the proper times upon the lever L' and assist the polarized relay B B' in overcoming the retracting-spring E³. For this purpose I make the lever L' the armature-lever of the local differentially-wound electro-magnet O, the circuit of one of whose differential coils passes, as

shown, through the contacts R R' of the relay C, while that of the other is constantly closed. Q represents the local battery, the current of which divides and passes through both coils of electro-magnet O in opposite directions so long as the contacts R R' are closed. When the circuit through R R' is broken the constantly-closed coil acts and the lever L' is attracted against the action of its spring E³, so that a prompt and certain break of contact is effected at K'. As will be readily understood, the retractor S for the neutral relay C is adjusted to such a strength that the contact R R' can be broken only by both batteries M B' M B². Said relay is not affected by the weaker current of positive main battery M B' or negative main battery M B².

The method herein shown of controlling the local electro-magnet O, which assists the relay B B', is but one of many that might be adopted in practice. The relay C might act in many other ways well understood by those skilled in the art, so as to energize said electro-magnet when the relay-armature is drawn forward. It will be seen, however, that the above arrangement possesses the special advantage that the magnet O is called into action the moment that the relay-armature of C begins to move. It is also to be noted that the energizing-coil on O, being always charged, is more ready to act with promptness when the circuit of the other coil is broken.

The general operation is as follows: When no current is upon the line the relay-contacts of A A' are held broken by the action of spring G. Contacts R R' are closed, and the armature-lever of B B' is drawn against contact-lever L' by spring D², but not with sufficient force to overcome the strength of spring E³. The local of sounder U is therefore broken and local battery P is shunted from sounder M. When key K' alone is closed battery M B' flows to line with a positive current, which closes contacts T³ T⁴, and sounder U responds. M is not affected, because positive current from M B' only is sufficient neither to separate points R R' nor to remove lever L' from its contact K'. When key K² alone is closed main battery M B² flows to line with a negative polarity, causing M to respond by breaking the connection between supplemental lever L and K. Contacts R R' are not affected, the current not being of sufficient strength, and contacts T³ T⁴ remain open because the current is not of the proper polarity. When both keys are closed together both batteries M B' M B² flow to line with a positive polarity, and both sounders U and M respond, the current being of proper polarity to close contacts T³ T⁴, and of proper strength, as well as polarity, to open contacts R R' and to carry the lever of B B' forcibly against supplemental lever L', so that the contact at K' is broken by the combined action of the relay armature-lever and the local electro-magnet O.

It is not regarded as necessary to show the sending and receiving apparatus complete at

both ends of the line. By the use of differential relays, rheostats, and condensers arranged so that the outgoing currents do not affect the home relays, two separate messages 5 may be sent and two received all on the same line and at the same instant of time.

While I have described the employment of a differential magnet, O, for assisting the relay B B, I do not limit myself to that arrangement 10 exclusively. Magnet O may be an ordinary local magnet, so connected that points R R', if broken, would shunt a local battery through it. I, however, deem the differential arrangement as shown and described the most efficient. 15

What I claim as my invention is—

1. The combination, with a duplex or multiplex telegraph relay, of a contact-lever for breaking and closing the local circuit of a receiving-instrument, an electro-magnet in another local circuit for assisting the relay in operating the contact-lever, and a supplemental relay controlling the circuits of said electro-magnet, and adjusted in the manner described 20 to render said magnet operative at the proper time to re-enforce the action of the first-named relay.

2. The combination, substantially as described, of two relays, an electro-magnet in a local circuit controlled by one of said relays, and an armature-lever for said electro-magnet, having contact points and stops in the local circuit for the other relay, and arranged to be also operated by said latter relay. 30

3. The combination, substantially as described, of a polarized relay, a supplemental contact-lever, and retractile spring therefor, applied, in the manner described, to stop the movement of the armature-lever under the action 35 of a current-strength corresponding to one transmitting-key, an electro-magnet acting upon the supplemental lever in conjunction with the relay, and a supplemental relay for controlling the local circuit containing said 40 electro-magnet, adjusted to respond only to a current of a greater strength.

4. The combination, substantially as described, of a polarized relay and armature-lever therefor, arranged to play between two supplemental levers, a retractor for one of said levers, adjusted below the strength of current corresponding to a current of one polarity, and of a strength corresponding to one transmitter, and a retractor for the other lever, adjusted 50 above the strength of the current of the opposite polarity sent by the other transmitting-key alone, as and for the purpose described. 55

5. The combination, substantially as described, of two supplemental contact-levers, closing, when against their stops, the short circuit of a local battery, a polarized relay-arma- 60

ture playing between said levers, retractors applied to said levers, so as to hold them in contact with their stops, and adjusted in the 65 manner described with relation to one another, a local electro-magnet for acting upon the supplemental lever having the stronger retractor, and a supplemental relay controlling the local circuits for said electro-magnet. 70

6. The combination, substantially as described, with a supplemental contact-lever for one relay, of a differentially-wound local electro-magnet acting upon the same, and a second relay whose back contacts are in circuit 75 with one of the coils of said electro-magnet.

7. The combination, substantially as described, of the polarized relay B B', having retractor D², supplemental levers L L', with retractors adjusted to different strengths of current, a differentially-wound local electro-magnet, O, and a relay controlling the same, whose retractor is adjusted above the weaker of the retractors for the supplemental levers. 80

8. The combination, substantially as described, of two polarized relays, one of which is provided with a supplemental contact-lever, a supplemental relay controlling the circuit of an electro-magnet whose armature is attached to said supplemental lever, and transmitting 85 apparatus adapted to send, when one key is depressed, a current of one polarity, when the other key is depressed a current of the opposite polarity, and when both keys are depressed together a current of greater strength than 90 that sent by either separately. 95

9. The combination of transmitters T' T², having respectively two and three sets of continuity-preserving transmitting-points, two main batteries, M B' M B², and connections, 100 as shown and described, whereby said batteries may be placed to line singly, one with a positive and the other with a negative polarity, according to which key is operated, and may be placed both to line, so as to re-enforce 105 one another when both keys are operated.

10. The combination, with a duplex or multiplex telegraph relay, of a contact-lever for controlling the local circuit of a receiving-instrument, an electro-magnet in a local circuit 110 for assisting the relay in operating the contact-lever, and means for rendering said electro-magnet operative, adjusted, in the manner described, to bring the same into action at the proper time to re-enforce the action of the relay. 115

Signed at Toledo, in the county of Lucas and State of Ohio, this 15th day of August, A. D. 1882.

CHARLES SELDEN.
